UNITED STATES PATENT OFFICE.

ALBERT VICKERS, OF WESTMINSTER, ENGLAND, ASSIGNOR TO VICKERS, SONS & MAXIM, LIMITED, OF WESTMINSTER, ENGLAND.

AUTOMATIC GUN.

SPECIFICATION forming part of Letters Patent No. 690,799, dated January 7, 1902.

Application filed October 29, 1900. Serial No. 34,825. (No model.)

To all whom it may concern:

Be it known that I, ALBERT VICKERS, steel-manufacturer, a subject of the Queen of Great Britain, residing at 32 Victoria street, Westminster, in the county of London, England, have invented certain new and useful Improvements in Automatic Guns, of which the following is a specification.

This invention has reference generally to automatic guns of the class or kind in which the breech mechanism is operated by means of a crank turned about its axis in one direction by the force of recoil and in the other direction by the reaction of a spring, most of the present improvements being particularly applicable to those guns which are constructed upon what is known as the "five-motion feed" principle—that is to say, those in which the lock is provided with a transversely-sliding cartridge-carrier that at each discharge of the gun acts, first, to draw a cartridge from the feed-belt; secondly, to lower the cartridge into position for loading; thirdly, to thrust it into the barrel; fourthly, to rise and seize a new cartridge, and, fifthly, to close firmly against the base of the cartridge in the cartridge-chamber after having fully completed its upward movement.

One of the chief objects of the invention is to so improve the construction of such guns, as hereinafter described, that the parts thereof will be much simplified both as regards their manipulation and assemblage, as well as their manufacture. The improvements are such that any one accustomed to the handling of an ordinary Maxim gun will have no difficulty in working the improved gun without requiring any fresh drill. At the same time most if not all of the disadvantages that have hitherto attended the working of the ordinary Maxim gun are avoided. It will be possible for the various parts of the lock to be assembled without the aid of any tools. It will be easier than heretofore to change the barrel. No riveting of the axis-pins of the pivotal parts of the lock is required, nor is there any necessity to fix the said axis-pins in place with retaining pins or wires, the said axis-pins being maintained in position by webs or fins on the side levers. The crank and connecting-rod are arranged to occupy a position of alinement with each other when

the breech is closed, so that the force of recoil exerted on the moving parts when the gun is fired will be augmented to such an extent as to overcome small obstructions to their movement, which might otherwise act to unduly retard the working of the gun. The cartridge-carrier stop hitherto used for limiting the descent of the carrier is now dispensed with, the function of this stop being performed by the upper surface of the carrier-guides on the recoil-plates. The joint of the toggle-links is constructed in such manner that at each discharge of the gun and the bending of the toggle-links the lock will not immediately leave the breech of the barrel, but will be maintained in its closed position for a sufficient length of time to permit the projectile to leave the barrel and the pressure of the powder gases to diminish. The lifting-levers and parts co-operating therewith for elevating the cartridge-carrier are so constructed that the said carrier is not only fully elevated prior to the final closing movement of the lock, as aforesaid, but is also firmly supported and locked to the lock-casing in the firing position without necessitating the construction of the said lifting-levers with sharp bearing-points and recesses, such as have been necessary in some forms of the lifting-levers hitherto used.

In order that my said invention may be clearly understood and readily carried into effect, I will proceed to describe the same more fully with reference to the accompanying drawings, in which—

Figure 1 is a side elevation. Figs. 2 and 2^a when taken together are a longitudinal section, and Fig. 3 a sectional plan, of a Maxim gun provided with various of the improvements above specified. Fig. 4 is a side elevation, and Fig. 5 a longitudinal section, of the lock detached and drawn on a larger scale. Fig. 6 is a rear elevation of the side levers provided with the aforesaid webs. Fig. 7 is a plan of the lifting-levers. Fig. 8 is a side elevation, and Fig. 9 a plan, of one of the recoil-plates. Figs. 10 and 13 are elevations showing in a somewhat-diagrammatic manner the lock and toggle-links of a Maxim gun provided with the improved joint, the former figure representing the breech closed and the latter the breech open. These figures also illustrate a modified form of the lifting-levers

and the toe-pieces working in conjunction therewith. Fig. 11 is a plan of the toggle-joint. Fig. 12 is an elevation of the lock, showing the said lifting-levers and toe-pieces 5 more clearly.

In all the figures like reference-letters indicate similar parts.

A A are the side plates of the casing, inclosing the breech mechanism. A' is the hinged 10 cover thereof.

B is the barrel.

C is the lock-casing.

D is the crank-shaft; D', the crank; D², the crank-handle; D³, the fusee.

15 E is the connecting-rod for coupling the crank to the side levers E' of the lock, said crank, connecting-rod, and side levers comprising the toggle-links hereinbefore mentioned.

20 F is the fusee-spring.

G is the water-jacket; H, the trunnion-block, having a hole h for the trunnion-pin employed for connecting the gun to its stand or support. I is the end cap of the said wa-

25 tter-jacket, through which the muzzle of the barrel passes and enters the muzzle attachment J through a stuffing-box.

K is the foresight.

L is the tangent-sight.

30 M is the firing lever or trigger.

N is the trigger-bar.

O is the handle-block by which the rear end of the casing inclosing the breech mechanism is closed.

35 P is the feed-block, and Q is the cartridge-ejector tube.

Referring more particularly to Figs. 1 to 3, the water-jacket G is made of steel, with its walls parallel, so that said jacket is cylind-

40 drical—that is to say, does not vary in diameter throughout its length, as in water-jackets formerly made. The trunnion-block H, to which the rear end of the water-jacket is connected, is made of reduced diameter, and the 45 forward end of the said jacket is “jumped up” or thickened on its interior at g. The shoulder g', which is thus formed, is curved,

50 as represented in Fig. 2, so that when the barrel is being inserted in place in the gun 55 the muzzle of the barrel will rise up the said curved shoulder, and will be thus directed into the conical opening i, leading to the stuffing-box i' of the end cap I. The barrel is thus capable of being much more rapidly inserted in place than heretofore. The brass

55 trough in the water-jacket is in the construction of gun represented by these figures dispensed with.

60 The center of the crank-pin lies horizontally opposite the center of the crank-shaft when the breech is closed for the purpose already stated, and the web in the crank is cut away to allow of the assembling of the recoil-plates and other parts with the crank in any

65 angular position relatively to the said recoil-plates.

The flanges, which are usually formed on

the outside of the recoil-plates or sliding frame a a, where they pass through the side plates A of the gun-casing adjacent to the 70 crank-shaft D, are dispensed with at top and bottom, and the flanges which have hitherto been provided at the upper side of the said recoil-plates next to the side plates A have also been dispensed with, the thickness of the recoil-plates being now approximately uniform 75 for almost their entire length. The lower right-hand corner a' of the said recoil-plates adjacent to the trunnion-block are now made with a curve of small radius a², Fig. 8. I leave 80 very little clearance between the edge a² of this slightly-curved corner and the sleeve b on the barrel, which construction enables the recoil-plates to be kept almost rigid with the barrel and greatly facilitates the assemblage 85 of the parts. The cartridge-carrier guides a³ on the upper edge of the said recoil-plates have been raised, for the reason hereinafter explained. The rear extensions a⁴ of the recoil-plates are located a short distance away 90 from the interior surface of the plates A A, so as to be out of the plane of the filling-in pieces a⁵, Fig. 2, which are situated behind the recoil-plates. These filling-in pieces are made with flanges a⁶ on each side thereof, by 95 which they are kept in place, instead of by means of a V-groove at their edges, as heretofore, the inside flanges being partly cut away in order to avoid the handle-block O, as best seen in Figs. 2 and 3. The guides 100 with which the side plates A have hitherto been provided for the recoil of the plates a are dispensed with.

The edge of the hinged cover A' now lies flush with the casing inclosing the breech mechanism for its entire length, the projections formerly provided on the side plates and the handle-block O being dispensed with to permit of this. The guide-blocks with which the sides of the said hinged cover A' have usually been provided are also dispensed with, as likewise are the recesses in the side plates for their reception.

The firing lever or trigger M is reduced in width at its lower end, as represented at m, 115 Fig. 2, where it is formed with a curved extremity, which is adapted to fit directly into a curved notch formed for its reception in the trigger-bar N, no connecting-pin being thus required. The trigger-bar is made of steel 120 and is not provided with the usual groove for the reception of the tail of the hand-sear. It is of the same width throughout its length except at the rear portion, where its width is reduced. (See Fig. 3.) The firing lever or 125 trigger M and the safety-catch R are held in place by split pins m' and r', respectively.

The ordinary rear guide-stud for the trigger-bar is dispensed with, the function of the said stud being performed by the under side 130 of the handle-block O being cut away to leave a passage between the lower end of the said handle-block and the upper surface of the plate A² of the casing, (see Fig. 2,) which

passage serves as a guide for the trigger-bar. The side flanges A^3 of the bottom plate A^2 extend backward for the full length of the side plates A , the handle-block O being modified in shape accordingly. The handle-block pin O' extends through the said flanges A^3 on the casing and is provided with a handle O^X for enabling the pin to be readily removed from the gun and replaced when desired. 5 As the said handle-block can thus be very quickly and easily removed, there is now no necessity to provide a spy-hole in the handle-block for looking through the barrel nor a shutter for closing the said spy-hole. Consequently they are dispensed with. 15

The tail-spring c' (see Fig. 5) of the cartridge-carrier C' is provided at the back thereof with a horn-piece c^2 , which by lying against the face of the lock-casing keeps the said tail-spring pressed forward against the carrier, with its toe-piece c^3 projecting beyond the said face. A longitudinal groove c^4 is formed in the front face of the lock-casing at such a position that when the carrier descends the aforesaid horn-piece will enter the said groove and remain therein during a portion of the movement of the said carrier; but when the carrier is near its lowest position the horn-piece c^2 rides up the incline c^4 at the bottom 25 of the slot c^4 , thereby locking the toe-piece c^3 . By this means the cartridge is retained firmly in the carrier until the said cartridge enters the ejector-tube Q and the carrier commences to rise. The tail-spring c' is riveted to the carrier, and the upper face of the toe-piece is made at an angle instead of with a curve, as are also both upper faces of the gib c^5 . The horns c^6 of the carrier are likewise of such shape that they lie flush with the top and 35 back faces of the carrier, whereby the said horns are possessed of increased size. The top face of the cam-guides a^6 occupy a lower position than heretofore in order to suit the increased size of the horns. The carrier-stop 40 is dispensed with, the upper faces of the guides a^2 on the recoil-plates (which are, as already stated, made higher than heretofore) serving to support and act as the stops for the carrier-horns. 45

50 The seating in the face of the carrier for the gib c^5 has been removed and the gib formed of a shape to fill up the gap thus obtained. (See Fig. 5.) The gib thus presents a continuous surface at c^7 to the cartridge-head and is able to hold the same more firmly and in a more truly horizontal position than heretofore.

The tumbler c^8 , the head-sear c^9 , and the safety-sear c^{10} are now held in position by 55 loose pins, which project slightly beyond the side plates of the lock-casing C . The pins for the tumbler and hand-sear each have a slightly-countersunk head, and the holes for them in the lock-casing are countersunk on both sides, so that the said pins can be assembled in either direction. The heads keep

them in position while the side levers and other parts of the lock are being assembled.

The lifting-levers C^2 are made in one piece with their pivot-pin, as shown in Figs. 4 and 7, and the lock-casing is cut away at c^{15} to permit of said lifting-levers being inserted into place, with the recessed portions c^{16} of their pivot-pin resting in the slots or spaces c^{17} , Fig. 5. The distance-piece hitherto used 70 on the lifting-lever pin is dispensed with, the shoulders formed by the recesses c^{16} and their engagement with the slots c^{17} serving the purpose of the distance-piece. The boss, which formerly only surrounded the hole for the lifting-lever pin, is now extended across the side of the lock-frame, as shown at c^{18} , Fig. 4. The lugs c^{19} on the sides of the carrier and with which the lifting-levers engage extend completely across the carrier, as shown in 85 Fig. 4, and the beveling on the sides of the carrier is now dispensed with. The stop c^{20} on the top front face of the lock-casing has been decreased in depth, and the part of the carrier which comes in contact with it is correspondingly increased for obtaining additional strength. For retaining the side levers E' connected to the lock-casing a cylindrical pin c^{21} , having a head at one end, is used, the levers being recessed on one side, as shown 90 at c^{22} , Fig. 6, so that the said pin can only be inserted from that side. The recoil-plate on the side adjacent to the head of the pin is formed with a rib a^7 , Figs. 8 and 9, in such a position that it lies close to the head of the 95 pin during the whole of the movement of the lock when the gun is working. The said pin is thus kept securely in position—on the one hand by its head and on the other by the said rib. The tumbler-pin and hand-sear pin are 100 kept in position by webs e , Figs. 4 and 6, depending from the side levers, a sufficient space being left between the side plates of the lock-casing and the toe-pieces of the side levers for the reception of these webs. The pin of 105 the safety-sear c^{10} is kept in position by a curved fin e' , formed at the forward end of the side levers E' , adjacent to their point of connection with the lock. The pin of the lock-mainspring c^{11} is dispensed with, the said 110 spring entering a recess formed in a block c^{12} , which is riveted to the lock-casing. (See Fig. 5.) This block c^{12} also serves as a guide for facilitating the assemblage of the parts of the lock. The ends of the lifting-levers C^2 where 115 they engage with the lugs c^{19} on the carrier C' are made flat instead of curved, as heretofore.

The connecting-rod E (see Figs. 10, 11, and 12) is formed with a slot e^2 , and the adjacent 120 end of the crank D' carries the crank-pin d^8 , which extends through this slot. The said crank is provided with one or a pair of studs or protuberances d^9 , and the connecting-rod 125 is formed with recesses e^3 e^4 , with which the 130 said protuberances coöperate.

On the firing of the gun the pin d^8 travels

in a downward direction in a circular course concentric with the center of the crank-shaft D, while the slotted end of the connecting-rod also travels in a downward direction in a circular course concentric with the center of the pivot e^x . The pin d^s therefore travels in the slot e^2 without at such time causing the toggle-links to withdraw the lock from the breech end of the barrel. Were it not for the pressure of the protuberances d^9 against the curved portion e^5 of the connecting-rod E during this free motion of the pin d^s the lock would not be held against the breech end of the barrel, and the pressure of the powder gases would be able to drive the lock away from the barrel, and the said gases would escape into the gun-casing; but the aforesaid protuberances by sliding against the portion e^5 of the connecting-rod compensate for the lost motion and keep the connecting-rod pressed forward and the lock tightly held against the barrel until the crank D' has traveled through a considerable angle, when the said protuberances enter the recesses e^4 and by the continued movement of the crank are caused to exert a pull on the connecting-rod, and thereby open the breech. At the reverse movement of the crank the said protuberances, by operating to push the connecting-rod forward, close the breech.

In order to enable the end of the crank D', carrying the protuberances d^9 , to be readily connected with the connecting-rod E, the said end of the crank is forked to embrace the adjacent end of the connecting-rod, as seen in Fig. 11, the said protuberances d^9 projecting inwardly from opposite sides of the fork, and the said pin d^s is separate from the other parts, so that it can be inserted in place after they have been coupled together.

The end e^{xx} of the toe-piece e^6 forms part of a curve struck from the center e^x , and the portion c^{13} of the lifting-lever C' on each side of the notch c^{14} is likewise curved in correspondence with the curved end e^{xx} of said toe-piece e^6 . When the carrier C' is depressed, the notch c^{14} in the lifting-lever lies adjacent to the edge e^7 of the toe-piece, and when the latter moves in the direction of the arrow, Fig. 11, which it does as the toggle-links straighten, this edge of the toe-piece acts on the notched portion of the lifting-lever and causes the latter to turn and elevate the carrier to its highest position before the lock closes the breech and the toggle-links straighten. The edge of the toe-piece then becomes disengaged from the notch, and the curved end e^{xx} travels over the curved portion of the lifting-lever without moving the latter during the final straightening movement of the toggle-links inclosing the breech. At the same time the sliding of the curved end e^{xx} over the curved portion of the lifting-lever effectually prevents the latter and the carrier from shifting their position relatively to the lock during the firing of the gun. In

this construction of the lifting-lever it will be seen that the curved end of the toe-piece does not engage with the notch c^{14} when bearing upon the curved portion of the lifting-lever, as was the case with the lifting-levers of a similar kind constructed heretofore.

e^8 is a stop against which the toggle-links strike when in their straightened position and by which they are prevented from rising too high in closing the breech.

What I claim, and desire to secure by Letters Patent of the United States, is—

1. In an automatic gun, the combination with the crank, the crank-shaft, the connecting-rod and the lock, of lifting-levers for the cartridge-carrier, formed with a transverse pivot-pin having recesses to engage with the inner ends of curved slots formed in the lock-casing substantially as and for the purpose specified.

2. In an automatic gun, the combination with the crank, the crank-shaft, the connecting-rod and the lock, of loose pivot-pins for the tumbler, the hand-sear, the safety-sear and the side levers, of webs and fins on the side levers and of ribs on the recoil-plates, the said webs, fins and ribs operating to retain the said loose pins in position in the lock substantially as described.

3. In an automatic gun, the combination with the crank-shaft, the crank, the connecting-rod, the side levers and the lock, of a protuberance on the crank, and of a slot in the connecting-rod, substantially as and for the purpose specified.

4. In an automatic gun, the combination with the crank-shaft, the crank, the connecting-rod, the side levers and the lock, of protuberances d^9 formed on the crank D', of a slot e^2 in the connecting-rod for receiving the crank-pin, of recesses e^3 e^4 for the protuberances, and of curved surfaces e^5 for the said protuberances to bear against during the free movement of the crank-pin in its slot e^2 substantially as and for the purpose specified.

5. In an automatic gun, the combination with the crank-shaft, the crank, the connecting-rod, the side levers, the lock, the cartridge-carrier and the lifting-levers therefor, of toe-pieces on said side levers, having curved extremities forming arcs struck from the pivotal axis of the side levers, of a notch in each of the lifting-levers for the edge of the said toe-pieces to engage with for actuating said lifting-levers, and of curved surfaces on each side of said notch, said curved surfaces forming arcs struck from the aforesaid pivotal axis of the side levers, substantially as described and for the purpose specified.

In testimony whereof I have hereunto set my hand in presence of two subscribing witnesses.

ALBERT VICKERS.

Witnesses:

E. D. LANG,
HENRY KING.
